UNITED STATES PATENT OFFICE

HENRI GOODMAN, OF SAN LUIS OBISPO, CALIFORNIA.

COMBINED STRAP AND WAISTBAND FOR PANTALOONS.

SPECIFICATION forming part of Letters Patent No. 321,962, dated July 14, 1885.

Application filed April 23, 1884. (No model.)

To all whom it may concern:

Be it known that I, HENRI GOODMAN, a citizen of the United States, residing at San Luis Obispo, in the county of San Luis Obispo and State of California, have invented certain new and useful Improvements in Pantaloons, &c., of which the following is a specification.

The object of my invention is to provide a means whereby pantaloons, overalls, drawers, and other like garments are sustained and supported about the person without the aid of suspenders or shoulder-straps. This object I accomplish by the means illustrated in the accompanying drawings, forming a part of this specification, and in which—

Figure 1 is a front view of a pair of pantaloons having my improvement attached thereto. Fig. 2 is a rear view of the same. Fig. 3 is a cross section taken through the pantaloons on a line with the waistband. Fig. 4 is a cross section of the loop, buckle, and its rollers.

Similar letters of reference are used to indicate like parts throughout the several views. 25 A and A' are two similarly-constructed straps, one of which carries a buckle, C, the other being adapted to enter the buckle as a tongue. These straps are situated on opposite parts of the waistband, are both 30 made of a double thickness of the fabric or material of which the garment is composed, and are of sufficient length to double back upon themselves. It is necessary, also, to make each of these straps somewhat wider 35 throughout one half of its length than through the other half, in order that the wider half may be stitched to the waistband and form a pocket, B, through which the other half of the strap can slip easily after it has passed around 40 the loop D.

D is a metal loop, which serves to admit the narrower lengths of the straps when they are being doubled back upon themselves, and which thus unites these doubled portions at 45 the back of the garment. The long arms of

the loop are provided with rollers or tubes E, which permit the doubled straps to move in the loop with ease, which affords a greater relief to the wearer than when the strap which surrounds the body is fixed and rigid.

In applying my invention to a garment the wider half of the strap A is first stitched to the waistband from the button-flap to a distance a few inches beyond the side seam. Thus the pocket or way B is formed. The 55 narrower length of the strap A is then passed through the metal loop D, and folded back through the mouth B' of the pocket B, and through this pocket until it emerges thence at the flap. By a similar construction the 60 pocket B and strap A' on the opposite side of the waistband is made. When it is desired to tighten the garment about the body, the only 65 requisite is to buckle together the ends of A and A' at or near the button-flap by suitable means provided. By drawing these two ends together the folded parts of A and A' will be tightened at the loop D, and the waistband 70 will be secured tightly around the body by once buckling, all necessity for any button upon the waistband being dispensed with.

Having thus described my invention, what I claim, and desire to secure by Letters Patent, is—

In pantaloons and like garments, the combination, with the waistband, of the straps A 75 A', buckle C, and loop D, a portion of each strap being doubled backward under another wider portion of itself, which is stitched to the waistband, and said straps being passed 80 through the loop at the back and secured by the buckle in front, substantially as shown and described.

In testimony that I claim the foregoing I have hereunto set my hand and seal.

HENRI GOODMAN. [L. S.]
